(57) **CLAIM**

The ornamental design for a clip for holding a bubble level vial, as shown and described.

DESCRIPTION

FIG. 1 is a front top perspective view of a clip for holding a bubble level vial showing my new design;

FIG. 2 is a front bottom perspective view thereof;

FIG. 3 is a rear elevation view thereof, including an exemplary bubble-level vial shown in broken lines;

FIG. 4 is a front elevation view thereof;

FIG. 5 is a left elevation view thereof;

FIG. 6 is a right elevation view thereof;

FIG. 7 is a bottom plan view thereof; and,

FIG. 8 is top plan view thereof.

The broken lines representing a bubble-level vial shown in FIG. 3 are for illustrative purposes only and form no part of the claimed design.
